(57) **CLAIM**

The ornamental design for a dock station, as shown and described.

DESCRIPTION

FIG. 1 is a perspective view of a dock station showing our new design;

FIG. 2 is a front elevational view thereof;

FIG. 3 is a rear elevational view thereof;

FIG. 4 is a right-side, elevational view thereof;

FIG. 5 is a top plan view thereof; and,

FIG. 6 is a perspective view thereof shown in use with a tablet computer being connected to the dock station.

The left side view is a mirror image of the right side view. Also, the broken lines in the drawings are directed to environment only and form no part of the claimed design.

1 Claim, 6 Drawing Sheets

FIG. 1
